UNITED STATES PATENT OFFICE.

THEODORE C. ROBERTS, OF NEW YORK, N. Y., ASSIGNOR, BY MESNE ASSIGNMENTS,
TO COLUMBIA PHONOGRAPH COMPANY, INC., A CORPORATION OF NEW YORK.

SPRING MOTOR.

Original application filed May 5, 1921, Serial No. 467,113. Divided and this application filed December 16, 1922. Serial No. 607,378.

To all whom it may concern:

Be it known that I, THEODORE C. ROBERTS, a citizen of the United States, and a resident of the city of New York, county 5 and State of New York, have invented certain new and useful Improvements in Spring Motors, of which the following, taken in connection with the accompanying drawings, is a specification.

10 This invention relates to improvements in spring motors, this application being a division of application, Serial No. 467,113, filed May 5, 1921. While such improvements are capable of more or less general 15 use, the present embodiment has been particularly conceived with reference to phonographic use, which requires certain features and refinements which may be desirable in other uses, but are not always essential. It 20 will, therefore, be understood that in describing the invention adapted to such use, that all other uses to which it may be put are comprehended.

An object of the invention is to provide a 25 motor capable of accurate regulation to constant speed, and to this end, the regulating means of the present embodiment includes a lever which is adapted to positively set the running speed of the motor to any 30 desired amount, and at the same time is capable of the most minute adjustment when it is desired to change the speed.

It is also an object to provide indicating 35 means in connection with the regulating lever, and means for adjusting the relation between the functioning parts of the regulating lever and the indicating means, whereby the accuracy of the indicator may be maintained.

40 With the above and other objects in view, embodiments of this invention are shown in the accompanying drawings, and these embodiments will be hereinafter more fully described with reference thereto, and the 45 invention will be finally pointed out in claims.

In the accompanying drawings—

Fig. 1 is a plan view showing part of the 50 upper side of a phonograph cabinet, provided with a motor embodying the present invention, but with the turntable removed, its position being indicated by dot-and-dash lines.

Fig. 2 is a vertical sectional view, taken

along the line 2—2 of Fig. 1, but showing 55 the turntable in position, and omitting the tone-arm with its sound-reproducer; and

Fig. 3 is a detail perspective view of the eccentric regulating bolt, which serves as 60 a bearing for the speed-regulating lever.

Similar reference characters indicate corresponding parts throughout the several figures of the drawings.

Referring to the drawings, the phonograph cabinet is provided in its top board 65 10 with a rectangular opening 11 through which the motor depends, a sheet-metal motor plate 12, preferably formed of pressed steel, extending over the opening and being secured to the top board adjacent the opening by screws 13. The plate is provided along its edges with a down-turned right angle flange 14, the longitudinal edges being parallel, the rear end portion being shaped as at 15, to provide a mounting for the tone-arm, while at its forward end it is provided with portions 16 and 17 concentric to the turntable, the flange 14 being cut away adjacent these portions—as at 18 and 19—to accommodate the ends of the manual start-and-stop lever and the speed-regulating lever, hereinafter more fully referred to. The plate has impressed along the portion adjacent the start-and-stop lever, the word 70 "start" and an arrow, and along the portion adjacent the speed-regulating lever, 75 calibrations having the letters S and F at the ends.

The motor carrying frame 21, preferably 80 formed of cast metal, is secured to the under side of the motor plate by bolts and nuts 22 passing through raised brackets 23 formed in the frame, and suitably insulated from the plate by felt washers 24 (Fig. 2), the upper surface of the frame being substantially flat and spaced from the motor plate, 85 as shown.

The frame is provided at its sides with opposed depending side portions 25 and 26 90 suitably reinforced, as at 27 and 28, by tapered enlargements to give the requisite strength and rigidity to prevent vibration. The side portion 26 is provided at its lower forward portion with a laterally extending shelf 29 projecting at right angles thereto, and adapted to support the bearing at the lower end of the vertical turntable shaft 30, 95 the upper end of which extends through and

is journaled in a flanged bushing 31 provided in the upper portion of the motor frame, and preferably formed of brass.

The driving springs are mounted in any suitable manner in a barrel 55 provided upon a horizontal shaft, the springs being wound through suitable gearing 58 and 59 by means of a winding shaft 153. A large spiral gear 72 is actuated by the unwinding 5 of the springs to drive the turntable shaft through intermediate gearing, consisting of a relatively small spiral gear 92 mounted upon a fixed horizontal shaft 87 and a relatively small spiral gear 93 meshing with the 10 worm portion 94 of the turntable shaft 30. Above the worm portion 94, the turntable shaft 30 is provided with a spiral gear 95 meshing with the worm 96 of the horizontal 15 governor shaft 97, journaled in the sides of the frame 21.

Governor shaft 97 is provided, at one end, with a disc 102, having its hub 103 slidable on the shaft, and to which bowed leaf springs 104 are connected at their outer ends, the 20 inner ends being connected to a stationary collar 105 fixed upon the shaft, centrifugal weights 106 being secured to the springs intermediate their ends. The governor parts are relatively light, so that there is very little vibration, noise, and danger of disarrangement in shipping.

A combined brake and speed-regulating lever 107 is pivotally mounted upon the frame at 108, and provided with a brake pad 109 25 adapted, when moved to the left, Fig. 1, to engage the governor disc to stop the motor, and when moved to the right, to limit the position of the disc—depending, of course, on its position of adjustment—and thereby regulate the speed of the motor.

Lever 107 is provided with an eccentric flange portion 110 for co-operation with the start-and-stop lever 111 and the speed-regulating lever 117. Lever 111 is pivotally 30 mounted at 112 upon the motor plate 12, has its long arm extending through the cut-out 18 in the edge of the motor plate, and is provided with a knob 113 disposed over the word "Start" inscribed on the plate. Upon 35 the end of the short arm of lever 111, there is pivotally mounted a spring pawl 114, provided at its inner end with a lug 115, (Fig. 2), yieldably held against the edge of lever 111 by a spring 116, the outer end 40 being projected toward the flange 110 of the brake lever. By moving the lever 111 to the left (Fig. 1), pawl 114 engages the flange 110 and moves the brake lever to braking 45 position, the yieldable movement of the pawl preventing excessive pressure on the brake pad, and the possibility of any damage that 50 might result therefrom.

The speed-regulating lever 117 is adjustably and pivotally mounted upon the frame 55 by means of a bolt 118, (see Fig. 3), adapted

to be adjustably fixed in position by a nut 159 at its threaded end engaging the under side of the motor frame and having an eccentric bearing shoulder 160 upon which the lever 117 is journaled. The lever is provided with an eccentric projection 119 at the end of its short arm; and at the end of its long arm, which extends through the cut-out 19 of the motor plate, there is provided an index pointer 120 which is bent about the 70 edge of the motor plate above the scale markings. If the speed of the motor is not exactly, at say 80 revolutions per minute with the pointer 120 at the center of the scale markings, it can be adjusted by turning the 75 eccentric bolt, accessible through the opening 161 of the motor plate, without removing the motor from the cabinet. As the 80 brake lever 107 is released by the start-and-stop lever 111, it is moved by the pressure 85 of the governor disc until the eccentric flange 110 engages the projection 119 of the speed-regulating lever 117; this point of engagement is varied by adjustment of said lever, to limit the movement of the brake lever 90 107, and thereby adjust the speed of the motor, as described above.

While there is illustrated and described preferred and satisfactory embodiments of this invention, it is obvious that changes 95 may be made therein which come within the spirit and scope of the appended claims.

Having now described the invention, what is claimed as new, and for which Letters Patent of the United States is desired, is:

1. In combination, a rotating element, a motor for actuating the rotating element, including a governor having a movable speed-regulating part, a brake shoe adapted to engage this part to stop the motor and to occupy varying positions to limit the movement of the speed-regulating part, and thereby, the speed of the motor, a regulating lever arranged to regulate the position of the brake shoe in its non-stopping position, and means adapted to be actuated to move the brake shoe to stopping position.

2. In combination, a rotating element, a motor for actuating the rotating element, including a governor having a movable speed-regulating part, a brake shoe adapted to engage this part to stop the motor and to occupy varying positions to limit the movement of the speed-regulating part, and thereby, the speed of the motor, a regulating lever arranged to regulate the position of the brake in its non-stopping position, and a manual start-and-stop lever adapted to be engaged with the brake shoe to retain it in stopping position, and to be released from the brake shoe to permit it to move to its non-stopping position.

3. In combination, a rotating element, a motor for actuating the rotating element, including a governor having a movable

speed-regulating part, a variable limiting member adapted to determine the running zone of this part, a regulating lever adapted to adjust the position of the limiting member, and means adapted to stop the motor.

4. In combination, a rotating element, a motor for actuating the rotating element, including a governor having a movable speed-regulating part, a variable limiting member adapted to determine the running zone of this part, a regulating lever adapted to adjust the position of the limiting member, and means adapted to stop the motor at will.

5. In combination, a rotating element, a motor for actuating the rotating element, including a governor having a movable speed-regulating part, a variable limiting member adapted to determine the running zone of this part, a pivoted regulating lever having an eccentric portion adapted to be engaged by the limiting member, the regulating lever adapted to vary the position of engagement of the limiting member with the eccentric portion, and means adapted to stop the motor.

6. In combination, a rotating element, a motor for actuating the rotating element, including a governor having a movable speed-regulating part, a brake shoe member adapted to engage this part to stop the motor, and to be released therefrom to permit starting, and a pivoted start-and-stop lever cooperatively related to the brake shoe member, adapted in one position to move it to stopping position, and in its other position to release it.

7. In combination, a rotating element, a motor for actuating the rotating element, including a governor having a movable speed-regulating part, a brake shoe member adapted to engage this part to stop the motor, and to be released therefrom to permit starting, and a pivoted manual start-and-stop lever cooperatively related to the brake shoe member, adapted in one position to move it to stopping position, and in its other position to release it.

8. In combination, a rotating element, a motor for actuating the rotating element, including a governor having a movable speed-regulating part, a brake shoe adapted to engage this part to stop the motor, and to be released therefrom to permit starting, and a manually operable lever adapted to actuate the brake shoe to stop and starting position, including a yieldable contact member adapted to engage the brake shoe with yielding pressure.

9. In combination, a rotating element, a motor for actuating the rotating element, including a governor having a movable speed-regulating part, a brake shoe adapted to engage this part to stop the motor, and to

be released therefrom to permit starting, and a manually operable lever adapted to actuate the brake shoe to start and stop position, including a spring-controlled contact pawl adapted to engage the brake shoe member with yielding pressure.

10. The combination with a rotating element, of a brake, a member cooperating therewith and adapted both to stop the rotating element and to regulate its speed, the said member being mounted for rotating movements solely.

11. The combination in a motor, of a governor having a movable speed-regulating part, a regulating lever adapted to determine the playing position of such part, and means for changing the pivotal axis of the regulating lever to change its regulating effect.

12. The combination in a motor, of a governor having a movable speed-regulating part, a pivoted regulating member adapted to determine the playing position of such part, and means for changing its pivotal axis to adjust its regulating effect.

13. The combination in a motor, of a governor having a movable speed-regulating part, a pivoted regulating member having a portion adjustable about the pivot to variably determine the playing position of the movable speed-regulating part, and a rotatable adjustable eccentric pivot bearing for the regulating member adapted to be adjusted to change the regulating effect of the regulating member.

14. The combination in a motor, of a governor having a movable speed-regulating part, a regulating member adapted to determine the playing position of such part, and having an index pointer, a scale for the index pointer, and means for adjusting the regulating member to synchronize its regulating effect with the scale and index relation, the adjustment having no effect upon the relationship of the regulating means and index pointer.

15. The combination in a motor, of a governor having a movable speed-regulating part, adjustable means adapted to occupy varying positions to contact with and limit the movement of the speed-regulating part, and thereby, the speed of the motor, a regulating lever arranged to regulate the position of the adjustable means, and means for changing the pivotal axis of the regulating lever to change its regulating effect.

16. The combination in a motor, of a governor having a movable speed-regulating part, a brake-lever adapted to engage this part to stop the motor and to occupy varying positions to limit the movement of the speed-regulating part, and thereby, the speed of the motor, a regulating lever arranged to regulate the position of the brake-lever in its non-stopping position, including

- an eccentric portion adapted to be engaged by the brake-lever, and means for changing the pivotal axis of the regulating member to change its regulating effect.
17. The combination in a motor, of a governor having a movable speed-regulating part, a brake-lever adapted to engage this part to stop the motor and to occupy varying positions to limit the movement of the speed-regulating part, and thereby, the speed of the motor, a regulating lever arranged to regulate the position of the brake-lever in its non-stopping position, including an eccentric portion adapted to be engaged by the brake-lever, and a rotatable adjustable eccentric bearing adapted to be adjusted to change the axis of the regulating member, and thereby, its regulating effect.
18. The combination in a motor, of a governor having a movable speed-regulating part, a regulating member adapted to determine the playing position of such part, an index-pointer carried by and non-adjustable with respect to the regulating member, a scale for the index-pointer, and means for adjusting the regulating member to synchronize its regulating effect with the scale and index relation.
19. The combination in a motor, of a governor having a movable speed-regulating part, a regulating member adapted to determine the playing position of such part, an index-pointer carried by and non-adjustable with respect to the regulating member, a scale for the index-pointer, and means for changing the pivotal axis of the regulating member to synchronize its regulating effect with the scale and pointer.
20. A spring motor embodying the features of claim 18 and mounted upon a frame secured to a sheet metal motor-plate for supporting the structure in position.
21. In combination, a spring motor including a governor having a movable speed-regulating part, a lever adapted positively to set the running speed of the motor and adjustable for variations of speed, a variable limiting member adapted to determine the running zone of this part and adjustable by the lever, and a separate means adapted to engage the limiting member to stop the motor.
22. In a spring motor, according to claim 21, the combination with the rotating element of a member cooperating therewith and adapted both to stop the rotating element and to regulate its speed.

Signed at New York, in the county of New York and State of New York, this 12th day of December, A. D. 1922.

THEODORE C. ROBERTS.
